AMOS F. DIXON, OF NEWARK, NEW JERSEY, ASSIGNOR TO WESTERN ELECTRIC COMPANY, OF NEW YORK, N. Y., A CORPORATION OF ILLINOIS.

PROCESS FOR MAKING TERMINAL BANKS.

1,127,741.

Specification of Letters Patent. Patented Feb. 9, 1915.

Application filed February 26, 1912. Serial No. 679,945.

To all whom it may concern:

Be it known that I, AMOS F. DIXON, citizen of the United States, residing at Newark, in the county of Essex and State of New Jersey, have invented a certain new and useful Improvement in Processes for Making Terminal Banks, of which the following is a full, clear, concise, and exact description.

10 This invention concerns selector switches such as are used in automatic telephone exchanges, and has to do particularly with the process of making the terminal boards thereof, that is, the boards which carry the multi-tipped line terminals.

In constructing terminal boards composed of alternate layers of sheet metal and insulation, great difficulty is encountered due to the variations in thickness of the insulating sheets and of the sheets of metal. Since these variations are cumulative, it becomes impossible to stack up any considerable number, one above the other, so that the centers between terminals and consequently also the overall dimension will be at all uniform. It can be readily appreciated that if the rubber or mica or other insulating material should vary even, say, half a thousandth of an inch, by the way a small 30 commercial variation, the cumulative variation on such a mass of terminals as used on an ordinary board would be very great and make successful construction well nigh impossible. The present invention overcomes 35 this difficulty and enables the production of a cheap and efficient terminal board.

Considered broadly, the invention consists in the process of superposing sheets of flexible insulating material, such as paper, 40 coated with a plastic insulating compound, and sheets of terminal forming metal, and applying pressure to the resulting structure until the overall dimensions are reduced to the desired amount. It is a peculiarity of 45 this process that, in the finished product so formed, not only may the overall dimensions be regulated with extreme nicety, but the distance between the individual strips is equally and uniformly reduced to the required figure. I may use a compound which 50 is originally sufficiently plastic for the purpose, but which dries and hardens when exposed to the air for a sufficient period, or more preferably, I may use a compound 55 which becomes plastic when subjected to

heat and which hardens sufficiently to maintain rigid the terminal sheets when allowed to cool. It is desirable that the compound be non-hygrosopic and have first-class insulating qualities; also that these qualities 60 be stable.

In the drawings, Figure 1 is a front elevation of a portion of the completed terminal bank; and Fig. 2 is a perspective view of the superposed sheets during the process 65 of assembly.

Referring to the drawings, 10 designates a punching of sheet metal preferably having ears or lugs adapted to form the contact terminals t t^1 t^2 . The ears upon each 70 metallic strip form multiple terminals of the same line on both faces of the board, so that each line is accessible to every brush on both sides of the board. A line may have but a single terminal t or may consist of 75 what are known in telephony as the tip, ring and sleeve terminals, t , t^1 , t^2 . Attention is called to the peculiar formation of the sheet metal strip 10. It will be noted that the stock is present only where it is needed, 80 and is omitted at all other places. This reduction in area of the metal surface effectively eliminates or at least greatly lowers the mutual capacity between the sheets of insulation. While not so desirable from 85 a manufacturing standpoint, wire may be substituted for the sheet metal. The sheets of metal after being punched into shape are stacked up alternately with paper coated with an insulating compound which is or 90 may be caused to become plastic.

Paper, as is well known is one of the few substances which can be manufactured in sheets which vary but little in thickness. It is also a first-class insulator. Therefore I 95 prefer to use paper as a base for the insulating compound.

A very desirable compound may be made from elaterite fused with linseed oil, but it is of course understood that any equivalent 100 compound may be used without departing from the scope of the invention. The resultant insulating elements consisting of the paper sheet and its compound are then stacked up alternately until the desired 105 number of terminals is obtained. A convenient method of doing this is shown in Fig. 2 and consists in perforating the metal sheets 10 and insulating elements 11 and 110 threading them upon sleeves 12, 12' of insu-

lation slipped over the rods 13, 13' secured at their lower ends to the base 18', and when the required number has been built up, the top plate 18 is secured in place. As many 5 bolts 13 and their sleeves are provided as may be necessary. The resultant structure is then placed between heavy iron clamps, (not shown) and heated so that the insulating compound becomes somewhat viscous, 10 and pressure is applied by means of the clamps until the required overall dimension is reached.

The rod 13 is threaded at its ends to receive nuts 20, 20' and the rod 13' is threaded at its ends to receive the nuts 19, 19'. After the required overall dimension is secured, and before the pressure of the clamps is removed, the nuts are screwed upon the bolts. The bolts 17, 17' are spacers, having 20 shoulders engaging the upper and lower cross bars for the purpose of limiting the amount of compression to insure the proper overall dimensions and consequently the proper distance between individual sheets. 25 They are provided with nuts 21, 21' and 16, 16 respectively. The heating process may then be discontinued. The compound thereupon hardens and the board is then removed

from the clamps a solid, homogeneous mass having uniformly-spaced, projecting lugs. 30

I claim:—

1. The process of making terminal boards consisting of superposing flexible insulating sheets coated with a plastic insulating compound and metal strips, and subjecting the 35 structure thus built up to pressure.

2. The process of making terminal boards consisting in superposing flexible insulating sheets coated with a plastic insulating compound and metal having projecting lugs, and 40 subjecting the structure thus built up to pressure.

3. The process of making terminal boards consisting in superposing in alternate layers, 45 sheets of paper coated with a plastic insulating compound and sheets of metal having projecting lugs, subjecting the structure thus built up to pressure in the presence of heat to uniformly space the terminal sheets, and finally allowing same to cool. 50

In witness whereof, I, hereunto subscribe my name this 24th day of Feb. A. D., 1912.

AMOS F. DIXON.
